[57] **CLAIM**

The ornamental design for a wall mounted luminaire, as shown and described.

DESCRIPTION

FIG. 1 is a perspective view of a wall mounted luminaire of the new design;

FIG. 2 is a front elevational view thereof;

FIG. 3 is a top plan view thereof;

FIG. 4 is a side elevational view thereof;

FIG. 5 is a bottom plan view thereof;

FIG. 6 is a top plan view of a second embodiment of my new design;

FIG. 7 is a side elevational thereof, the opposite side being a mirror image;

FIG. 8 is a bottom plan view thereof; and,

FIG. 9 is a rear elevational view common to both embodiments.

It is understood that the front of the second embodiment is identical to that of the first as shown in FIGS. 1 and 2.

The broken lines are shown for illustrative purposes only and form no part of the claimed design.
